DUAL HORIZONTAL FLUTED PUSH BAR

John J. Grove, Dallas, Tex., assignor to Facade, Inc.,
Richardson, Tex., a corporation of Texas

Filed June 24, 1963, Ser. No. 75,494

Term of patent 14 years

(Cl. D10—8)

FIG. 1

FIG. 2

FIG. 4

FIG. 3

FIG. 1 is a perspective view of the push bar with a central member facing outward;

FIG. 2 is a perspective view of the push bar with a central member facing inward;

FIG. 3 is an end view of the push bar; and

FIG. 4 is a top view of the push bar with a portion of the bar broken away for convenience of illustration.

I claim:

The ornamental design for a dual horizontal fluted push bar, as shown and described.
